UNITED STATES PATENT OFFICE.

NATHANIEL J. PRITCHARD AND JAMES S. TEMPLON, OF MILNES, ASSIGNEES,
BY DIRECT AND MESNE ASSIGNMENTS, TO THE PRITCHARD BRAKE COMPANY,
OF ROANOKE, VIRGINIA.

AUTOMATIC PISTON FOR AIR-BRAKES.

SPECIFICATION forming part of Letters Patent No. 399,157, dated March 5, 1889.

Application filed November 21, 1887. Serial No. 255,790. (No model.)

To all whom it may concern:

Be it known that we, NATHANIEL J. PRITCHARD and JAMES S. TEMPLON, citizens of the United States, residing at Milnes, in the county of Page and State of Virginia, have invented certain new and useful Improvements in Automatic Pistons for Air-Brakes; and we do hereby declare the following to be a full, clear, and exact description of the invention, such as will enable others skilled in the art to which it appertains to make and use the same.

This invention relates to an automatic air-piston for use in pneumatic railway-brakes for the purpose of controlling the admission of air to the brake-cylinder; and it consists, essentially, in the construction, arrangement, and combination of parts, substantially as will be hereinafter described, and then set forth in the claims.

In the annexed drawings, illustrating the invention, Figure 1 is a vertical section of our improved "automatic air-piston" for pneumatic railway-brakes, and shows the piston at the upper limit of its stroke. Fig. 2 is a horizontal section on the line *x* *x* of Fig. 1. Fig. 3 is a vertical section similar to that shown in Fig. 1, with the piston at the lower limit of its stroke. Fig. 4 is a detail elevation of the air-supply pipe and the pipe which leads to the brake-cylinder, together with other connections. Fig. 5 is a sectional detail of certain of the pipes, and shows the arrangement of the plug-valve when the device is to be used with "straight air."

Similar letters of reference denote corresponding parts throughout the several figures.

A represents a cylinder of any suitable dimensions and made in any desired manner, it being adapted to be arranged in an upright position beneath the car with which it is used. It may be made in one or more parts. In the drawings the preferable construction is shown, consisting of the main cylindrical body, upon the top of which is a cap-plate, A', having an interiorly downward projection, *b*, which limits the upward movement of the piston within the cylindrical chamber.

The bottom of the cylindrical part A is closed by means of a plate bolted thereto, which 50 carries a bulb-shaped air-chamber, B. This chamber receives at the bottom any drippings or other waste which may accumulate therein, whence they are removed by a drain-cock, *a*.

The cylinder A is provided with ports where the several pipes are coupled that constitute the ordinary air-brake and lead to the parts of the same.

Thus C denotes the port where coupling is 60 made with the pipe which leads to the air-drum.

D is the port where the pipe is connected leading to the brake-cylinder.

E is a port located in the side wall of the 65 bulb B, and at this point the pipe F enters, which leads to the main air-supply pipe, and through it air is introduced into the device. At port D is connected a T-shaped pipe, as will be seen by reference to Figs. 2 and 5. 70 This pipe has a horizontal portion running outward from the cylinder A, and at right angles to this horizontal portion is another horizontal part, H. At the intersection of these two parts is located a plug-valve, G, 75 which can be turned in the position shown in Fig. 5, where air will pass through the pipe H, communication being shut off from the port D; or said valve may be turned in the position shown in Fig. 2, where air will pass 80 between the port D and the pipe I, which leads to the brake-cylinder, and is coupled to one end of the pipe H.

A short distance below the port D, in the wall of the cylinder A, is located an exhaust-port, *e*. A vertical passage, *c*, extends upward through the wall of the cylinder A from the bottom of said cylinder to the port C. Near the bottom of the cylinder communication is established between the interior chamber thereof and the passage *c* by a port, *d*.

Within the central chamber is located a piston, K, which is preferably a double piston, having the lower head, L, and the upper head, M. The head M is flanged circumferentially 95 at top and bottom, or otherwise suitably fash-

ioned and shaped to permit an encircling ring, N, to be loosely arranged about the same, said ring being recessed for a portion of its circumferential distance, as will be seen by reference to Figs. 1 and 2. The piston has a vertical movement up and down within the central chamber, and in said movement it comes into proper relation to the several ports and passages, hereinabove mentioned, to accomplish the results which will be farther on more specifically stated. When the piston occupies its uppermost position, as seen in Fig. 1, air can easily pass from the brake-cylinder through pipe I into port D, and round past the recessed face of the encircling ring N into the exhaust-port e, where it will escape into the atmosphere. When the piston is in its lowermost position, as shown in Fig. 3, air will pass through port C, over the air-drum, into the interior chamber, and out through port D into the brake-cylinder, where it will set the brakes.

As already stated, pipe F connects with the main air-supply pipe and serves to introduce air into the air-chamber. Air thus introduced will pass upward in the direction shown by the arrows, Fig. 1, into the interior chamber of the cylinder, push the piston upward until it passes beyond the port d, and then go into the passage-way c up into the air-drum. It will also fill the space above the piston, so that said piston will be balanced.

Suppose now that it is desired to set the brakes. If straight air is to be used, all that need be done is to have the valve G located in the position shown in Fig. 5. Then the engineer by manipulating the valve upon the locomotive will cause air to rush through the supply-pipe until it reaches the pipe H, through which it will pass, as shown by the arrow, Fig. 5, onward into the pipe I, and thus to the brake-cylinder. When automatic air is to be used, the plug G will be turned to occupy the position shown in Fig. 2. If it is desired to set the brakes automatically, the engineer will exhaust air by properly manipulating his valve, so that there will be less pressure beneath the piston than there is above it. This will cause the piston to descend until it reaches the position shown in Fig. 3, where it has passed down so low as to cease to cover the port D; hence air coming under pressure from the air-drum into the chamber above the piston will pass out through the port D and rush into the brake-cylinder and set the brakes.

It will be noted that the encircling ring, which is loosely arranged about the head M of the piston, enables our device to be susceptible of great delicacy of movement, for, supposing the piston to be in the position shown in Fig. 1, the exhausting of a small amount of air from beneath it will cause it to drop enough to cover the port d. A fall of the piston far enough to enable the head L to cover the port d will not displace the ring N from

its position, as it will be seen there is sufficient space between the ring N and the encompassing flange of the head to permit this movement.

It has already been seen that the head M of the piston has an encircling ring loosely arranged about it, said ring being contained in an annular space in the piston-head. The vertical length of this packing-ring is shorter or less than the vertical length of the annular space within which it is contained, as will be perceived upon an inspection of Fig. 1 or 3; hence it is evident that the piston may have a certain amount of vertical movement independent of any corresponding movement on the part of the packing-ring. The piston may move, therefore, to a certain extent without displacing the packing-ring from its position. The provision of this ring enables our device to be susceptible of great delicacy of movement, for, supposing the piston to be in the position shown in Fig. 1, it is evident that the exhausting of a very small amount of air from beneath it will cause it to drop far enough to cover the port d. The piston in falling in this manner, however, will not displace the packing-ring, as the difference in vertical lengths between the packing-ring and the annular space within the piston-head is sufficient to permit of enough movement on the part of the piston to close port d without interfering with the position of the packing-ring.

In Fig. 1 the parts are shown in the position occupied when air is passing out of the brake-cylinder through the exhaust, on the one hand, and air, on the other hand, is entering through the main pipe into the air-chamber and up into the air-drum. The engineer by exhausting a very small portion of air from beneath the piston can close the port d in the manner just stated, and yet will not interfere with the position of the packing-ring which connects ports D and d. When the double-ended piston goes down farther, of course the ring N will be carried with it.

When the engineer desires to relieve the brakes, he will of course manipulate the valve upon the locomotive so as to introduce air once more below the piston to cause the same to rise, so that communication may be had between the port D and the exhaust-port, when the air will readily pass from the brake-cylinder into the atmosphere.

We hereby disclaim the construction shown in the patent to Boyden, No. 280,285, June 26, 1883, and in the English Patent No. 3,000 of 1879.

Having thus described our invention, what we claim as new, and desire to secure by Letters Patent, is—

In a device for applying and relieving the air-pressure on railway-brakes, the combination of the inclosing-case A, whose top plate, A', has a downward projection, b, said case having port C, leading to the air-drum, port

D, leading to the brake-cylinder, port E, where the main pipe enters, the exhaust-port *e* in the side wall of the cylinder near port D, the vertical passage *c* and port *d* between it and the interior chamber of the case, the T-shaped pipe connected to the casing at port D, and having a plug-valve, G, located at the intersection of its members, the piston K within said interior chamber of the casing, having heads L and M, the loosely-placed ring N, surrounding head M, and having a recessed face adapt-

ed to connect port D and exhaust-port *e*, all of said parts being arranged to operate substantially in the manner and for the purpose described.

In testimony whereof we affix our signatures in presence of two witnesses.

NATHANIEL J. PRITCHARD.
JAS. S. TEMPLON.
